H. DE V. PERRY

RHEOSTAT

Filed Nov. 1, 1922

INVENTOR:

Harold De V. Perry

BY

Walter A. Knight

ATTORNEY.

UNITED STATES PATENT OFFICE.

HAROLD DE VEAU PERRY, OF CINCINNATI, OHIO, ASSIGNOR, BY MESNE ASSIGNMENTS, TO SKYLARK RADIO CORPORATION, A CORPORATION OF DELAWARE.

RHEOSTAT.

Application filed November 1, 1922. Serial No. 598,333.

To all whom it may concern:

Be it known that I, HAROLD DE VEAU PERRY, a citizen of the United States, residing at Cincinnati, in the county of Hamilton and State of Ohio, have invented new and useful Improvements in Rheostats, of which the following is a specification.

My invention relates to rheostats, of a horizontal type, and is especially adapted 10 for use on radio receiving sets.

My improved device is very rugged and compact, occupies a small panel space and is composed of a small number of simple parts.

15 The complete length of the resistance unit may be covered in one motion, whereas, other types in general use require a plurality of movements.

My invention is illustrated in the accompanying drawings in which:

Figure 1, is a perspective of a portion of the front panel of a radio receiving set, showing my improved rheostat in position for use,

25 Fig. 2, is a top plan view of the device and a section thru the panel at the place of attachment,

Fig. 3, is an under plan view of the rheostat,

30 Fig. 4, is a rear elevation of the device, and

Fig. 5, is a section on the line 5—5 of Fig. 3.

Referring now to the drawings, A is a 35 flat rheostat base of suitable insulating material, with the portion back of the supporting panel B a section of a larger circle than the front portion. Into the center of the two circles composing the periphery of the base A is moulded a brass insert a and axially threaded to receive the pivot bolt a^1 , on which the contact lever F is pivoted with the spring washer a^2 to give the required tension and after the bolt has been adjusted 45 it is held securely in position by the lock nut a^3 .

The contact lever F extends in both directions from the pivot, without the panel to a handle f, and within to make contact with. 50 the wires c^1 of the resistance element C, which has an insulating core c, secured at each end to the base A.

The element C is preferably placed directly opposite the part of the base A that 55 protrudes thru the panel B so that the po-

tential rotary movement of the lever F by means of the handle f carries the contact point f¹ thru the whole arc of the element F.

Terminal lugs E, E¹ have wires w, w secured to them in any usual way, and extend below the base A and resistance element C, to form stops and limit the rotation of the contact lever F. The stop E is electrically connected with the contact lever F by the connector D. A single screw secures 60 E, the outer end of D and one end of c to the base A. Another screw secures E¹ and the other end of c to A.

The top of the outer port of the base A is graduated for convenience in adjusting 70 the contact lever F to a secure amount of resistance desired.

I claim as my invention and desire to secure Letters Patent of the United States:—

1. A rheostat comprising an insulating 75 base with a resistance element on one section of the periphery only and an opposite arc of said periphery thru which the handle portion of a contact lever may be rotated, a contact lever pivoted at or near its middle and having a contact point on the resistance end and an insulated handle on the other end and means for making electrical connection to the contact lever and to the resistance.

2. A rheostat comprising an insulating 85 base with a resistance element on one section of the periphery only and a reading scale on the opposite arc of said periphery thru which the handle portion of a contact lever may be rotated, a contact lever pivoted at or near its middle and having a contact point on the resistance end and an insulated handle on the other end, a terminal lug at the open end of the resistance element, a connector between the contact lever and said 90 terminal lug and a terminal lug at the closed end of the resistance.

3. A rheostat comprising an insulating 100 base with a resistance element on one section of the periphery only and a reading scale on the opposite arc of said periphery thru which the handle portion of a contact lever may be rotated, a contact lever pivoted at or near its middle and having a contact point on the resistance end and an insulated handle 105 on the other end, a terminal lug at the open end of the resistance element, a connector between the contact lever and said terminal lug, a terminal lug at the closed end of the resistance, said terminal lugs forming steps 110

to limit the rotation of said contact lever.

4. A rheostat comprising an insulating base with a resistance element on one section of the periphery only and a reading scale on the opposite arc of said periphery thru which the handle portion of a contact lever may be rotated, a contact lever pivoted at or near its middle, and having a contact point on the resistance end and an insulated handle on the other end, a connector between the contact lever and a terminal lug at the open end of the resistance element a terminal lug at the closed end of the resistance, said terminal lugs forming clamping plates to secure the resistance to the base and also stops to limit the rotation of said contact lever.

5. A rheostat comprising an insulating base with an arc on the rear portion and another arc on the opposite front portion, the arc on the front being of lesser radius than that on the rear, a resistance element on the rear arc, a contact lever pivoted substantial-

ly at the middle of said base, having a contact point on the resistance end and an insulated handle on the outer end, and means for making electrical connection to the contact lever and to the resistance.

6. A rheostat comprising an insulating base with an arc on the rear portion and another arc on the opposite front portion, the arc on the front being of lesser radius than that on the rear, a resistance element on the rear arc, a contact lever pivoted substantially at the middle of said base, having a contact point on the resistance end and an insulated handle on the outer end, a reading scale contiguous to said front arc, an indicator on said handle adapted to be used in conjunction with said scale, and means for making electrical connection to the contact lever and to the resistance.

In testimony whereof I have hereunto set my hand.

HAROLD DE VEAU PERRY.
